Attorney

UNITED STATES PATENT OFFICE.

JOHN ANGUS MACDONALD, OF BLAIRMORE, ALBERTA, CANADA.

SHOT-FIRING DEVICE.

1,377,086.

Specification of Letters Patent.

Patented May 3, 1921.

Application filed September 9, 1920. Serial No. 409,244.

To all whom it may concern:

Be it known that I, JOHN ANGUS MACDONALD, a subject of the King of Great Britain, residing at Blairmore, Province of Alberta, Canada, have invented certain new and useful Improvements in Shot-Firing Devices; and I do hereby declare that the following is a full, clear, and exact description of the invention, such as will enable others skilled in the art to which it appertains to make and use the same.

The present invention relates to improvements in shot firing devices.

The primary object of the invention is the provision of a shot firing device including a battery box, means for containing batteries, and means for closing the circuit and electrically firing a shot.

Another object of the invention is the provision in a device such as above referred to of a safety means for rendering premature firing of the charge impossible.

A further object of the invention is the provision of a shot firing device including a battery box having batteries therein, and spring contact members for closing the circuit of the batteries normally held out of contact, and means for connecting the current conveying wires to one set of spring circuit closing members.

A still further object of the invention is the provision of a shot firing apparatus such as above referred to which will be comparatively simple and inexpensive to manufacture, eliminating a number of the parts in usual devices of this construction, and which will be reliable and efficient in use and readily operated.

With the above and other objects in view, the present invention resides in the novel features of construction, formations, combinations and arrangements of parts to be hereinafter more fully described, claimed, and illustrated in the accompanying drawings forming a part of the present application and in which:

Figure 1 is a perspective view of a portion of a shot firing device constructed in accordance with the present invention;

Fig. 2 is a longitudinal sectional view thereof;

Fig. 3 is a detail sectional view illustrating one of the operating plungers in circuit closing position; and,

Fig. 4 is a fragmental portion of the cover showing the safety slide.

Referring now to the accompanying drawing by corresponding characters of reference throughout the several views, the numeral 1 denotes in general a battery box, the upper portion only of which is shown, as the box itself forms no part of the invention.

The box 1 is provided with a suitable closure 2 hinged at one end at 3 to the upper edge of the box 1. One or more batteries 4 shown at 4 may be placed within the box, the same having the usual terminals or contact posts 5 and 6 through which current is conveyed by means of the flexible conductors 7 to the charge which is to be fired.

The cover 2 directly above the contact posts 5 and 6 is provided with openings 8 which may be closed by slides 9 mounted in guides 10 secured to the upper side of the cover 2.

Plungers 11 are mounted in alignment with the openings 8 to pass therethrough and are supported at the upper ends of the springs 12 which are secured to the cover 2 in concentric relation to the openings 8 by any suitable means.

The springs 12 which support the plungers 11 also carry handles or knobs 13 preferably of cork; the bodies 14 and the metal facings 15 on the same may be constructed of any other desired non-conducting material.

The conductors 7 previously referred to have secured to their inner ends collars 16 which are slipped over the plungers 11, and when the wires or conductors 7 are inserted between the upper convolutions of the spring, these collars 16 form a contact means for securing the said conductors to the plungers.

Contact plates 17 are supported by springs 18 beneath the openings 8. These plates 17 are yieldingly forced against the insulating washers 19 secured to the inner sides of the cover 2 and which hold the contact plates 17 out of engagement therewith. The springs 18 are secured to the upper portion of the batteries 4 in any suitable manner and surround the contact posts 5 and 6, as clearly shown in Fig. 1.

When it is desired to fire a charge, the slides 9 are drawn to the position shown in Fig. 4 which leaves the plungers 11 free to pass through the openings 8 into contact with the members 17. Further pressure upon the knobs 13 will force these contact members downwardly into engagement with

the posts 5 and 6, thereby closing the circuit and firing the charge. Such position is clearly shown in Fig. 3 of the drawing.

When the slides 9 are moved inwardly to close the openings 8, it will be obvious that the plungers 11 will be prevented from entering the openings 8 and engaging the contact members 17, thus preventing any premature firing of the charge. It will be understood in this connection that the device described as a shot firing apparatus can also be used for lighting purposes, or, in fact, any other purpose to which the various parts thereof will adapt themselves.

From the foregoing description, taken in connection with the accompanying drawing, it will be manifest that a shot firing device is provided which will fulfil all of the necessary requirements of such a device, and it should be understood in this connection that various minor changes in the specific details of construction can be resorted to within the scope of the appended claims without departing from the spirit or sacrificing any of the advantages of the invention.

Having thus fully described the invention, what I claim as new and desire to protect by Letters Patent is:—

1. In an apparatus such as described, a battery box and a cover for the same, batteries disposed within the box and having contact posts extending therefrom, plungers movable through the cover to and from the contact posts, contact members interposed between the contact posts and plungers and yieldingly held out of engagement with the contact posts, and conductors connected with the plungers.

2. In a device such as described, a battery box having a cover and batteries disposed within the battery box, said cover having openings therein, contact posts extending from the batteries in alinement with the

openings of the cover, springs secured to the cover, plungers carried by the springs and adapted to pass through the openings in the cover toward the contact posts, spring contact members disposed between the contact posts and plungers, and conductors leading from the plungers.

3. In an apparatus such as described, a battery box including a cover, batteries within the battery box, contact posts provided upon said batteries, said cover having openings therein with which the contact posts align, springs carried by the cover and surrounding the openings, plungers carried by the springs and adapted to pass through said openings, said springs normally yielding the plungers above the openings, contact members disposed within the cover between the contact posts and the plungers, and yieldingly forced away from the contact posts toward said cover, conductors leading from the battery box, eyes secured to the conductors and surrounding the plungers with said conductors passed through the upper convolutions of the springs which support the plungers and means for preventing engagement of the plungers with the contact members.

4. In a device such as described, a battery box including a cover, batteries within the box and having contact posts, plungers movable through openings formed in the cover to and from the contact posts, slides secured to the cover to close said openings and prevent the plungers from entering the battery box, and conductors extending from the plungers.

In witness whereof I have hereunto set my hand.

JOHN ANGUS MACDONALD.
